United States Patent Office.

F. B. MORSE, OF PLANTSVILLE, CONNECTICUT.

Letters Patent No. 96,251, dated October 26, 1869.

IMPROVED SERIES OF DIES FOR FORMING KING-BOLTS.

The Schedule referred to in these Letters Patent and making part of the same.

To all whom it may concern:

Be it known that I, F. B. MORSE, of Plantsville, in the county of Hartford, and State of Connecticut, have invented a new Improvement in Dies for Forging King-Bolts; and I do hereby declare the following, when taken in connection with the accompanying drawings, and the letters of reference marked thereon, to be a full, clear, and exact description of the same, and which said drawings constitute part of this specification, and represent, in—

Figure 1, the upper part, and

Figure 2, the lower part of the opening-die.

Figure 3, the upper, and

Figure 4, the lower part of the forming-die,

Figure 5, the upper, and

Figure 6, the lower part of the trimming-die.

Figure 7, the upper, and

Figure 8, the lower part of the die for completing the neck.

Figure 9, a longitudinal section of the last-named lower die.

Figure 10, the blank, as prepared for the first operation.

Figure 11, as opened by the first operation.

Figure 12, as from the second operation.

Figure 13, after the neck is formed by the last operation.

Figure 14, a top view of the bolt complete.

This invention relates to an improvement in the manufacture of the article of carriage-hardware, known to the trade as "king-bolts," and it consists in a series of dies for forging the said bolts.

The blank, as seen in fig. 10, is forged in the usual manner. The head split, then heated, is placed into the die A, fig. 2, when the follower, or other part, B, of the die is struck on to it, the central portion *a* passing down into the slit and opening the ends, as seen in fig. 11, partially forming the head, then removed to the die C, fig. 4, which is formed so as to spread

the head of the bolt and shape the outer surfaces of the two ends above the head.

Set into this die, the follower or other part, D, is struck on to the blank forming it, as seen in fig. 12, and spreading the head, as denoted at *d d*, fig. 14. Then the bolt is placed into the trimming-die E, fig. 6, and the follower F struck thereon to cut away the fin, or surplus metal. Then the neck of the bolt is formed up to the broken line, fig. 13, by means of the dies commonly used for this purpose, or other suitable dies.

To complete the head above that line, the bolt is placed into the die G, fig. 8, which is constructed as seen in fig. 9, so that when the bolt is placed therein, a movable part, H, of the die is placed in against the neck, to complete the die around curved part of the neck previously formed, so that in the completed die, that part of the neck above the said broken line is formed, the movable part H permitting the insertion and removal of the bolt from the die, when the bolt has thus been placed in the said die. Then the follower or other part, I, of the die is struck thereon and the head is finished.

Thus, by these several operations, the bolt is finished complete, including the neck.

By preference, I employ the opening-dies, shown in figs. 1 and 2, yet it will be evident that the dies in figs. 3 and 4 may be employed as the opening-die, and thus dispense with the opening-die.

In application A, filed in even date herewith, the dies shown in figs. 3, 4, 5, and 6, are made the subject of the said application for patent, but in that operation the neck is not complete.

I claim, as my invention—

The series of dies C D, E F, and G I, constructed as described, to form king-bolts for carriages.

F. B. MORSE.
